UNITED STATES PATENT OFFICE

1,998,498

TYPEWRITING MACHINE

Harry A. Foothrap, Harrisburg, Pa., assignor, by mesne assignments, to Underwood Elliott Fisher Company, New York, N. Y., a corporation of Delaware

Original application December 31, 1925, Serial No. 78,665, now Patent No. 1,909,148, dated May 16, 1933. Divided and this application March 29, 1930, Serial No. 440,143

10 Claims. (Cl. 197—65)

My invention relates to improvements in typewriting machines, and more particularly to carriage retracting mechanisms and controlling means therefor.

5 The principal object of the invention, generally stated, is to provide a simple and efficient form of motor driven carriage retracting mechanism, controlled automatically by the typewriter carriage, in either of the two extreme positions there-
10 of, and controllable independently in intermediate positions of the carriage.

Another object is to provide for locking the carriage feeding mechanism during operation of the carriage retracting mechanism.

15 Other objects will appear as the succeeding description is developed, and in this connection, it is to be noted that the particular embodiment of the invention disclosed herein is especially adapted for use in connection with a type of 20 machine disclosed more in detail in my copending application, Serial No. 78,665, filed December 31, 1925, now Patent No. 1,909,148, issued May 16, 1933, of which the present application is a division.

In the accompanying drawings:

25 Figure 1 is a front elevation, with unimportant parts broken away, illustrating my invention in its preferred application, that is, to the machine of the above noted patent,

Figure 2 is a view in rear elevation with parts 30 broken away,

Figure 3 is a view in side elevation,

Figure 4 is a plan view more particularly of the carriage retracting mechanism and carriage lock,

35 Figure 4a is a detail section of a clutch mechanism forming part of the carriage retracting mechanism.

Figure 5 is an elevation of the structure shown in plan in Figure 4,

40 Figure 6 is an elevation of the carriage lock,

Figure 7 is a plan view of the same,

Figure 8 is a rear elevation of the carriage feeding mechanism and the associated carriage lock, and,

45 Figures 9, 10, 11, 12, 13, and 14 are related views of parts of the carriage lock.

Referring to the drawings, the machine to which my invention is shown as applied is, generally speaking, of the commercially known Elliott-
50 Fisher type, developed and equipped for posting telephone toll slips at high speed.

The pedestal members 1 (Figs. 1, 2 and 3) support a frame 2, carried by brackets 3 extending inwardly from said members 1, the frame
55 including side members 4 and 5 rigidly connected

together in spaced apart relation, and to the brackets 3, by front and rear transverse bars 6 and 7. The frame 2, in turn, supports the front and rear carriage guides 8 and 9, respectively, of an Elliott-Fisher typewriter carriage 10, the construction and equipment of which is well known and need not be entered into in detail. It is sufficient, for present purposes, to say that the carriage 10 is equipped with the usual recording mechanism, including a series of type arms 11 and operating keys 12, by the manipulation of which, letters and numerals may be printed in the usual way.

The carriage 10 is advanced by a spring drum 13 connected thereto by a tape 14, and this movement is controlled by the usual carriage feeding mechanism which includes a feed rack 15 carried by the rear carriage guide 9 and geared to the carriage 10 through the medium of a key-operated escapement mechanism, shown in Fig. 8, and 20 fully described in United States Letters Patent No. 1,203,519. The carriage 10 is advanced and retracted over a combined form table and flat platen 16 (Fig. 1) supported by the transverse frame bar 6, and over which the forms or slips 25 are fed between edge guides 17 and 18. After the forms or slips are printed, they may be ejected from the table and platen 16 into a receptacle 19 supported beneath the table by plates 20 and 21 secured to the frame members 4 and 5. 30

There is an automatic form feeding mechanism in this machine operated by the carriage, which need only be described briefly in passing, to impart a full understanding of the general organization of the machine. This feeding mechanism 35 includes a set of feed rolls 22 (Fig. 1) mounted upon a feed roll shaft 23, journaled in the plates 20 and 21 at the rear of the combined table and platen 16. A presser roll 24, mounted in a frame 26, swinging on the shaft 27, Fig. 3, is tensioned 40 by a suitably connected spring 28, Fig. 2, to clamp the form or slip against the feed rolls 22. A one way clutch 29 (Fig. 1) on the feed roll shaft 23 is connected by a depending arm 30 (Fig. 2) and draw rod 31, to one arm of a lever 32 fulcrumed 45 at 33, the remaining arm of which is suitably connected at 34 with a bail 35 (Figs. 2 and 5) mounted to swing against the tension of a spring 36. When the carriage is retracted to begin a new line, a projection 37 thereon engages a cam 38 on the 50 bail 35 and swings the latter, whereupon the feed roll shaft 23 is rocked, through the described connecting devices, sufficiently to feed the form or slip one line space.

An ejector key 39, (Figs. 1 and 3) and a release 55

key 40, operate the feed rolls 22 and presser roll 24, respectively, to effect release of the form by said rolls, and to eject the form from the combined platen and table 16 into the receptacle 19.

5 The ejector key 39 is operatively connected to a one way clutch 41 on the feed roll shaft 23 by suitable connections designated as a whole by the numeral 42. The release key 40 operates connections designated by the numeral 43, to rock the shaft 27 to lift the presser roll 24 and release the work. The numerals 44 and 45 (Fig. 2) designate automatic skip space mechanism, and 46, 47 and 48 indicate tabulator stops and a tabulator key, respectively, all of which units are merely noted 10 in passing and form, per se, no part of the present invention. The foregoing statement is likewise true of the tax meter 49 (Fig. 1) and its operating keys 50 and 51 with which this machine is equipped.

15 Coming now to the carriage retracting mechanism, a motor 52, (Figs. 1, 2 and 3), preferably electric, is supported in the rear of the machine by a drop bracket 53 and is connected by a belt 54 to a drive wheel 55 journaled on a shaft 56 afforded suitable bearings on the left hand frame member 4 (see Fig. 3). The front end of the hub 57 of the wheel 55 constitutes the loose member 58 of a clutch 59 whose fixed member 60 is fast to the shaft 56. Engagement and disengagement of the 20 clutch 59 controls the driving of the shaft 56 by the motor 52 which is preferably continuously operating under the control of a switch 61 (Fig. 3) mounted on the pedestal 1. When the clutch is disengaged, the wheel 55 rotates idly on the shaft 56, but upon the engagement of the clutch, the shaft will be rotated to drive the carriage retracting pinion 62 (Figs. 4 and 5) keyed to the front end of the shaft 56 and engaging a carriage retracting rack 63 fixed to the traveling carriage 10.

25 It is intended that the carriage 10, upon reaching its forward limit of movement, will automatically cause the engagement of the clutch 59 and thus initiate the retraction of said carriage 10, by the motor 52, and automatically disengage said clutch 59 when the limit of the retractile movement of the carriage is reached. To this end, a clutch operating lever 64, of bell crank form, is fulcrumed at 64a on a bracket 65 extended from 30 the frame member 4, and is provided with a stud 66 (Figs. 4 and 4a) engaging an annular groove 67 in the hub 57 of which the loose member 58 of the clutch is a part. A spring 68 attached to one end of the lever 64 and to a latch lever 69 pivoted at 69a to the bracket 65, tends to swing the lever 64 in the direction to slide the loose member of the clutch along the shaft 56 to engage its coacting member 60. This tendency is resisted by the latch lever 69 which, by interlocking engagement with a projection 70 on the clutch lever 64, normally holds the latter in the disengaged position shown in Fig. 4. In this figure, the carriage rack 63 is shown in the position it assumes immediately prior to reaching the limit of the printing movement of the carriage 10. In this position, it will be seen that a tappet on the carriage, in the form of an adjustable screw 71 carried by the rack 63, is engaged with the short front end 71a of the latch lever 69 so that upon the next forward movement of the carriage 10 in letter spacing direction, the tappet 71 will contact the forward arm 71a of the latch lever 69 and swing said latch lever against the resistance of the spring 68 to release the clutch-operating lever 64 and enable

the spring 68 to rock the lever and engage the clutch.

The motor 52, operating through the belt 54, pulley 55, clutch 59, shaft 56, pinion 62 and rack 63, will now return the carriage 10 to the left in Fig. 4. When the limit of the retractile movement is approached, a tappet 72 (Figs. 4 and 5) on the carriage 10 will engage an adjustable contact, as a screw 73 carried by the front end of the clutch lever 64 and the final retractile movement 10 of the carriage will swing the clutch lever 64 against the resistance of the spring 68, to disengage the clutch 59 and enable the latch lever 69 to reengage the projection 70 and hold said clutch 15 disengaged.

It is sometimes desirable to shorten the travel of the carriage, and to bring the carriage retracting mechanism into operation before the carriage has reached the limit of its normal travel in letter spacing direction and effected its automatic 20 return. I, therefore, provide a hand control for the clutch 59, in the form of a carriage return lever 74 (Figs. 2, 3 and 5) fulcrumed at 74a on a bracket 75, and having its lower end 76 disposed to engage the end 71a of the latch lever 69 for 25 the purpose of moving the latter to its idle position to release the clutch lever 64 when the up-standing portion of the lever 74 is grasped by the operator and swung in opposition to the spring 77 (Fig. 5). The movement of the lever 30 74 is limited by a stop 78.

It is desirable to lock the feeding mechanism of the carriage 10 against any attempt to operate it during carriage retraction. I, therefore, provide a carriage feed lock in the form of a lever 35 79, Figs. 6 to 14, fulcrumed on the back of the carriage at 80, with its rear end disposed to engage an abutment or trip 81 carried by the fixed part of the structure in such position that the final advance movement of the carriage in letter 40 spacing direction will bring the rear end of the lock lever 79 into engagement with the trip 81 and cause the lever to be swung from its normal position, shown in Fig. 4, and in full lines in Fig. 7, to its operative position, indicated in dotted lines in Fig. 7. There is a second abutment or trip 82 similar to the trip 81, which is engaged by the lever 79 upon retraction of the carriage 10 contact with which shifts the lever to its inoperative position. In its operative or locking 50 position, the lever 79 obstructs the operative movement of the escapement designated 83 (Fig. 8). For this reason, the lever 79 is so mounted that when swung to its operative position, it will lie over and in obstructing relation to 55 a set collar 84 fixed to the draw rod 85 of the spacing dog 86 of the carriage escapement to prevent longitudinal movement of the draw rod, and hence, preventing the release of the escapement under the action of the keys or spacing 60 key. The escapement locking lever 79 is yieldingly retained in its two positions by a spring catch 87 (Fig. 10).

The carriage feed lock is thus latched by the catch 87 in its ineffective position during the advance of the carriage, but is automatically brought into action to lock the carriage feeding mechanism against operation as soon as the forward movement of the carriage is completed, and holds the feeding mechanism locked against inadvertent operation until automatically released at the limit of the return movement of the carriage.

What I claim is:

1. The combination with a travelling carriage 75

provided with a rack, of a carriage retracting motor, driving and driven clutch members, a pinion movable with the driven clutch member and engaging the rack, and means controlling the engagement and disengagement of the clutch members, said means including, clutch control members projecting into the vertical plane of the rack, and members movable with the rack to engage said clutch control members and cause the engagement of the clutch members at one limit of the rack movement and the disengagement of said clutch members at the opposite limit of the rack movement.

2. The combination with a carriage movable back and forth, and provided with a rack, and a continuously running motor, of operating connections between the carriage and motor, including a clutch, a tensioned clutch-shifting lever moving in one direction to shift the clutch, a clutch latch, and means mounted upon the carriage rack for engaging the clutch latch and subsequently moving the tensioned clutch lever in the opposite direction.

3. In a machine of the class described, the combination with a carriage adapted for advance and retraction, a carriage-retracting motor, and driving connections between the motor and the carriage, including a clutch; of clutch-control mechanism, including clutch-shifting and clutch-latching levers, respectively, the clutch-shifting lever being movable to engage and disengage the clutch, respectively, and the clutch-latching lever being movable into interlocking engagement with said shifting lever to retain the latter in clutch-disengaging position, a single tensioning device urging said latching lever toward interlocking position, and said shifting lever toward clutch-engaging position, and means to alternately move the latching lever from interlocking engagement and the shifting lever to clutch-disengaging position by advance and retraction of the carriage, respectively, and including tappets on the carriage directly engaging said levers.

4. The combination with a frame, a carriage adapted for advance and retraction thereon, and escapement mechanism on the carriage, including a draw rod, of motor-operated carriage-retracting mechanism, and carriage-operated mechanism for locking the escapement while said carriage is under the control of the motor, including a locking member on the carriage movable to engage and disengage said draw rod, and abutment members on the frame directly contacting said locking member to move the latter to engaging and disengaging positions at the limits of advance and retraction of the carriage, respectively.

5. The combination with a frame, a carriage adapted for advance and retraction thereon, and escapement mechanism on the carriage, including a draw rod, of motor-operated carriage-retracting mechanism, and carriage-operated mechanism for locking the escapement while said carriage is under control of the motor, including a locking member on the carriage movable to engage and disengage the draw rod, abutment members on the frame directly contacting said locking member to move the latter to engaging and disengaging positions at the limits of advance and retraction of the carriage, respectively, and cooperating means on said car-

riage and locking member to yieldingly retain the locking member in either of its positions.

6. The combination with a frame, a carriage adapted for advance and retraction thereon, and escapement mechanism on the carriage, a carriage-retracting motor, driving connections between the motor and the carriage including a clutch; of clutch control mechanism, including a single pair of clutch-disengaging and clutch-latching levers, respectively, means for operating said levers alternately to unlatch and disengage said clutch by advance and retraction of the carriage, respectively, including tappets on said carriage directly engaging said levers, an escapement locking member on the carriage movable to locking and unlocking positions, and abutments on the frame directly contacting said locking member during travel of the carriage to move said member to locking and unlocking positions in timed relation to unlatching and disengagement of said clutch, respectively.

7. The combination with a travelling carriage; a retracting motor therefor; and connections between the motor and carriage, including a clutch; of a clutch-operating lever, one arm of which engages one member of the clutch, and another arm of which projects into the path of travel of the carriage for operation thereby; and a latch also extending into the path of travel of the carriage for direct operation thereby, and normally adapted to maintain the clutch-operating lever in one of its adjusted positions.

8. The combination with a travelling carriage; of a motor drive for the carriage, including a clutch; a clutch-control lever directly connected to the clutch; a latch normally engaging the clutch-control lever; and operating devices for the lever and the latch, the operating devices wholly mounted on, and travelling with, the carriage, and adapted to directly contact the lever and the latch, respectively, during the carriage travel.

9. The combination with a travelling carriage; a carriage return motor; and driving connections between the motor and carriage, including fast and loose clutch members; of clutch-shifting mechanism, including separate clutch-control levers, one such lever being connected to the loose clutch member, and another of the control levers normally effective to retain the loose clutch member against movement in one direction; and tappets on the carriage to directly contact the respective clutch control levers for alternate operation during the travel of the carriage.

10. The combination with a travelling carriage; escapement mechanism to control movement of the carriage in one direction, including a pawl and a draft member connected thereto to trip the latter; a motor and connections between the motor and the carriage to return the carriage to the beginning of a line; of carriage-operated means to lock the escapement during the return travel of the carriage, including a normally idle locking member adapted to engage and disengage the draft member; and means between which and the locking member there is relative movement, to directly contact with the locking member and shift the latter into and out of effective position in timed relation with the carriage movement.
